UNITED STATES PATENT OFFICE.

JOSEPH TURNBULL AND EDWIN W. FARWELL, OF MINNEAPOLIS, MINNESOTA.

SNOW-ROAD MACHINE.

SPECIFICATION forming part of Letters Patent No. 434,963, dated August 26, 1890.

Application filed February 28, 1890. Serial No. 342,175. (No model.)

To all whom it may concern:

Be it known that we, JOSEPH TURNBULL and EDWIN W. FARWELL, citizens of the United States, residing at Minneapolis, in the 5 county of Hennepin and State of Minnesota, have jointly invented certain new and useful Improvements in Snow-Road Machines, of which the following is a specification.

Our invention relates to apparatus for 10 sprinkling roads to cause smooth road-beds to be produced by freezing. Great difficulty is experienced among the lumbermen in providing good roads for hauling logs from the different places where trees are felled to a common 15 depository. As is well known, the cutting of logs in northern regions is done mostly in the winter, for the reason that it is difficult to transport them except upon sleds, and to use these to advantage smooth road-beds, either of snow 20 or ice, are necessary. And as it frequently happens that there is too little or too much snow to form the desired roadways, it is found necessary to make roads by sprinkling a course and allowing a subsequent freezing to 25 produce the smooth surfaces required. Furthermore, it is found that the roadways so formed are smoother and better for the purpose of hauling logs than when the road-bed is formed merely by beaten snow. Ordinary 30 sprinklers are not adapted to the purpose, because the cold is often sufficient to freeze the water in the apparatus and thus end its usefulness. In addition to the formation of a smooth track for sleds it is frequently found 35 necessary to remove deep snow from the road-bed and from its sides to facilitate transportation.

It is the object of our invention to produce 40 an apparatus adapted to warm water sufficiently to prevent it from freezing while the apparatus is being operated and also to produce steam when desired, suitable appliances being provided whereby the road-bed may be 45 sprinkled with the warm water, and when occasion demands jets of steam may be thrown into the road and to its sides for melting away snow.

Our improvements are illustrated in the 50 accompanying drawings, in which— Figure 1 is a plan view of the apparatus; Fig. 2, a side elevation, partly in section; Fig.

3, a rear elevation; Fig. 4, a top view of the funnel for conducting water into the boiler; and Fig. 5 is a detail of one of the sprinkling-nozzles.

In said drawings 1 designates a boiler, having a semi-cylindrical top and vertical sides 2. A passage-way 3, for the products of combustion, is formed by vertical sides 4, separated from but connected at the bottom with the outer sides 2 of the boiler, and the sides 4 are connected at the top by a crown-sheet 5. A continuous water-chamber is thus formed at the sides and over the combustion-chamber. A suitable grate 6 near the rear end is provided, and also a door 7 for closing the fire-chamber. At the forward end is connected a smoke-stack 8, having a hinge 9, by means of which its upper portion can be swung rearward. The boiler is supported upon bobsleds 10, or runners of any desired character. Short pipes 11 are connected to the boiler near its middle, and valves 12 are provided for regulating or cutting off the flow of water. From the pipes 11, which may have T-shaped connections 13, there extend downward and rearward pipes 14, which may be provided at their lower extremities with any suitable character of nozzles or sprinklers for directing the water downward or laterally.

At the top of the boiler is connected a pipe 15, controlled by a valve 16, for using steam when desired. This pipe has connections 17, extending to the pipes 14, so that steam can be carried to the lower end of the latter pipes.

In using steam for removing snow or other purposes the lower ends of the pipe 14 may be connected by a transverse pipe 18, having suitable perforations for ejecting steam in the directions desired. The pipe 18 and the nozzles 19 may be used interchangeably by coupling them to the pipes 14 by any of the usual forms of couplings.

The boiler is supplied with water through the funnel 20 in the top.

Devices are shown by means of which a barrel of water can be hoisted and emptied into the funnel. These devices consist of a post 21, having lateral braces 22, and provided with a pulley 23 at its top, through which a rope or chain may be run for hoisting a barrel to the funnel. A man-hole 24,

with which the funnel connects, is closed by a removable plate 25 and secured by any suitable clamping devices 26.

In use water can be easily kept from freezing while the apparatus is in operation, and in case of the obstruction of the road by snow steam can be readily utilized for removing so much of it as may be an obstruction.

Practical use has demonstrated that the apparatus is highly successful and useful for the purpose for which it is intended.

Having described our invention, what we claim, and desire to secure by Letters Patent, is—

15 In an apparatus of the character set forth, a portable horizontal boiler having a flue

at its base extending from end to end, and water-chambers above and at both sides of the flue, water-pipe connections in the boiler sides above the flue, and steam-pipe 20 connections in the top, valves therefor and connecting-pipes extending downward near to the ground, and interchangeable water-sprinklers and steam-sprayers therefor, substantially as and for the purpose set forth.

JOSEPH TURNBULL.
EDWIN W. FARWELL.
